UNITED STATES PATENT OFFICE.

HOLDRIDGE G. GREENE, OF ONEIDA, NEW YORK, ASSIGNOR TO TRIUMPH TRAP CO., INC., OF ONEIDA, NEW YORK, A CORPORATION OF NEW YORK.

PROCESS OF FORMING JAWS FOR GAME TRAPS.

1,413,722.

Specification of Letters Patent. Patented Apr. 25, 1922.

Application filed April 12, 1920. Serial No. 373,054.

To all whom it may concern:

Be it known that I, HOLDRIDGE G. GREENE, residing at Oneida, in the county of Madison and State of New York, have invented certain new and useful Improvements in a Process of Forming Jaws for Game Traps, of which the following is a specification.

This invention relates to a new and improved process of forming blanks of sheet metal, and in the present embodiment of my invention I propose to illustrate and describe it as adapted to form blanks out of which jaws of game traps are constructed.

One of the objects of the invention is to provide a process of forming blanks out of sheet metal, such as steel, which not only minimizes a waste of raw material, but which is carried on by a single continuous operation, and wherein the tools required for carrying on this operation are so simple that a minimum amount of repairs is required to maintain the tools in an operative condition.

Another object of the invention is to provide a process of forming blanks for jaws of game traps wherein the right and left hand jaws for a game trap are separately produced and separately discharged, thereby making it unnecessary to assort the form blanks preliminary to further operations.

Other objects and aims of the invention more or less specific than those referred to above, will be in part obvious and in part pointed out in the course of the following description of the steps and the relation of each step to one or more of the others thereof employed in carrying out my process, and the scope of protection contemplated will be indicated in the appended claims.

In the accompanying drawings, wherein I have illustrated preferred forms of embodiment of my invention:

Figure 1 illustrates the male die employed in carrying out my improved process.

Figure 2 illustrates the female die employed in carrying out said process.

Figure 3 is a bottom plan view of Figure 1.

Figure 4 is a bottom plan view of Figure 2.

Figure 5 illustrates a strip of metal, suitable for utilization in carrying out my improved process, and showing one stage of the process.

Figure 6 is a view of the same blank at a further stage in the process.

Figure 7 is a similar view of the blank in still a further stage in the process.

Figure 8 shows the blank preliminary to completing the final step of the process; and

Figure 9 is a plan view showing one of the completed blanks ready to be formed into a trap jaw.

Referring now to the drawings, wherein similar reference characters refer to similar parts throughout the several views thereof, the reference numeral 1 denotes a plate or base member upon which is mounted the dies or punching members 2, 3 and 4.

5 indicates another plate or base member, in which is formed apertures 2', 3' and 4'. These apertures constitute the female part of the die employed in carrying out my improved process. The punch 3 co-operates with the aperture 3', the punch 4 co-operates with the aperture 4'.

It will be understood that in practice these dies are mounted one above the other on the respective jaws of a press, so that when the press jaws are reciprocated, the punches will be caused to make and enter the correspondingly formed recesses or apertures located directly therebeneath.

In carrying out my process a strip of material, preferably steel, is employed, said strip being cut to the exact width required for blanking out a pair of trap jaw blanks, that is to say, the blank is of such width as will permit the same to be split longitudinally to provide the aforesaid blanks. This strip, which is designated as 6, is fed endwise into the press to be engaged by the punches, 85

80 suitable guides, of course, being provided to determine the position in which the blanks shall be inserted between the jaws of the press. When the strip is inserted it first encounters the punches 2 and 3, the punch 95

2 cutting from the blank the small triangular part 7, and the punch 3 cutting therefrom the small substantially square portion 8. The part 7 cut from the blank is waste material, and the part 8 is merely a sufficient 100 portion cut from the blank to trim the starting end of the material with a minimum loss.

When this operation has been accomplished by a single stroke of the press, the strip is 105 then moved forwardly to its second station. In this operation, that is to say, upon the next operation of the press jaws, the end

of the punch 4 merely splits longitudinally the surplus overhanging stock shown at 9 in the dotted lines of Figure 6, the punches 2 and 3 operating to cut from the blank the 5 waste portions indicated in Figure 6 at 10 and 11.

It will be noted that at this stage the parts 12 and 13 of the strip are connected at 14 with sufficient material to hold said 10 parts together so that the strip can be moved onwardly or forwardly to the third station.

When the strip 6 is in the third station, the die or punch 4 shears and separates two blanks, as shown in Figure 7, said blanks 15 being designated 15 and 16, the blank 15 being shown in dotted lines, being forced entirely through the female part of the die, and the remaining waste material indicated at 17, being separated from the end of the 20 blank.

It will, however, be noted that the jaw blank designated at 16 is still attached to the adjacent material as at 14. The strip or bar is then moved into the fourth station, 25 in which station the cutting edge 18 of the die or punch shears the small remaining connection between the blank 16 and the connecting stock, discharging the jaw blank 16 in a separate chute. Thereafter the strip 30 or bar 6 is moved forwardly intermittently, there being one forward or onward movement of the stock for each operation of the press, whereupon at each operation of the press two jaws are formed, the jaws 15 being 35 discharged in the third station, and the jaws 16 being discharged in the fourth station; and further, at each operation of the press the waste parts indicated at 10 and 11 are cut from the stock. The waste portions 9 40 and 17 are cut from the blank only at the initial operations, when the free end of the stock is being inserted into the press.

It will accordingly be seen that I have provided a process well adapted to attain, 45 among others, all the ends and objects of the invention above pointed out, in a very simple yet efficient manner. In carrying out the process it will be noted that save for the initial operation, when the waste is to be 50 cut from the end of the stock, the only waste or loss of material sustained is the two substantially triangular parts 10 and 11 which are cut from the stock in order to properly shape the trap jaw blanks.

55 It will also be noted that the operation is substantially a continuous one, the strip or bar being merely inserted between the jaws of the press and moved intermittently therein, whereby as above stated, two complete jaws are formed at each operation of 60 the press.

As many changes could be made in this construction without departing from the scope of the following claims, it is intended 65 that all matter contained in the above de-

scription or shown in the accompanying drawing shall be interpreted as illustrative only and not in a limiting sense.

Having thus described my invention what I claim as new and desire to secure by Letters Patent is:

1. The herein described process for forming the jaws of game traps, consisting in providing a strip of metal having the width of two blanks, preparing the end of the said strip by cutting out at one operation one corner portion and an edge portion on the opposite side near the said end leaving an unsevered portion at the end, then cutting off at one operation a part of the said unsevered end portion and cutting out portions on opposite sides of the strip at a distance from the said end, then at one operation splitting the strip longitudinally and cutting off the remainder of the unsevered 85 end portion and cutting out portions on opposite sides of the strip at a distance from the cut-out side portions first mentioned the said operation detaching one formed blank, and then at one operation splitting 90 the end portion of the strip longitudinally to the said cut out edge portions mentioned second and detaching the second and third blanks and forming cut out portions on opposite sides and at a distance from the 95 severed end of the strip.

2. The herein described process of forming blanks for the jaws of game traps, consisting in providing a strip of metal of a width equal to the width of two blanks, and 100 as a first step cutting away at one operation a portion of one corner of the end of the strip and a portion of the opposite edge of the strip near the said end leaving a portion of the end of the strip unsevered, then advancing the strip and as a second step at one operation cutting off a part of the said unsevered portion at the end of the strip and cutting out portions adjacent to each other on opposite sides of the strip and at a 105 distance from the said end, again advancing the strip and as a third step at one operation cutting off the remainder of the said unsevered end portion of the strip and shearing longitudinally the portion of the strip ex- 115 tending between the said end and said adjacent cut out edge portions thereby detaching one formed blank and leaving the second formed blank unsevered and also cutting out adjacent portions on opposite edges of the strip as before at a distance from the said adjacent cut out edge portions first mentioned, and again advancing the strip and as a fourth step cutting off at one operation the said unsevered blank and shearing longitudinally the portion of the strip extending 120 to the said cutout edge portions mentioned second thereby detaching a third formed blank.

3. In a process for forming blanks for 130

the jaws of game traps, a die comprising male and female members, the male member having near one end twin right-angled triangular projections spaced apart and extending in different directions and having their bases aligned transversely of the said male member, the said member having also near the other end a third projection having the form of an elongated right-angled triangle with its base or shortest side parallel with the corresponding sides of the said twin projections, and the said female member having openings corresponding in contour to the said cutting projections of the male member.

4. The herein described process of producing blanks for the jaws of game traps, which consists in providing a strip of metal of a width equal to the width of two blanks, cutting away portions of the edges of given lengths of said blank, shearing each of said blanks longitudinally thereof to separate a

blank from said strip, and then shearing the remaining blank from said strip.

5. The herein described process of producing blanks for the jaws of game traps, which consists in providing a strip of metal of a width equal to the width of two blanks, cutting away portions of the sides of one length of said strip to form the end of one blank, simultaneously cutting away the portion of the opposite edge of the next preceding length of said strip to form the end of another blank, shearing the first mentioned length of said blank longitudinally to sever a jaw blank therefrom, and severing the next succeeding length from said first mentioned length to form another blank.

In testimony whereof, I affix my signature in the presence of two witnesses,

HOLDRIDGE G. GREENE.

Witnesses:

CHARLES H. WILSON,
F. E. ADAMS.
